UNITED STATES PATENT OFFICE.

GIOVANNI ANTOFILLI, OF NEW YORK, N. Y.

BURGLAR ALARM.

1,420,510.

Specification of Letters Patent. Patented June 20, 1922.

Application filed August 28, 1919. Serial No. 320,401.

To all whom it may concern:

Be it known that I, GIOVANNI ANTOFILLI, a citizen of the United States, residing at New York, in the county of New York and 5 State of New York, have invented certain new and useful Improvements in Burglar Alarms; and I do hereby declare the following to be a full, clear, and exact description of the invention, such as will enable 10 others skilled in the art to which it appertains to make and use the same.

This invention relates to an improved burglar alarm and one object of the invention is to provide a burglar alarm so constructed that an electro-magnet may be energized when it is attempted to open a door, the magnet when energized releasing a 15 spring controlled switch element to close the circuit of an electric bell thus permitting 20 the bell to ring.

Another object of the invention is to so construct this burglar alarm that the electric bell will continue to ring until the 25 spring controlled switch is manually returned to an inoperative position.

Another object of the invention is to so construct this burglar alarm that the magnet energizing circuit may be in circuit with 30 the battery for the bell ringing circuit.

Another object of the invention is to provide an improved type of contact element 35 for the electro-magnet energizing circuit and an improved actuating device for closing this contact, the contact being mounted upon the door jamb and the actuating element upon the door.

Another object of the invention is to so construct this contact and actuating element that the actuating element may be rendered inoperative in case it is desired to open 40 the door from the inside thus permitting the door to be opened from within the house without the alarm being sounded.

This invention is illustrated in the accompanying drawings wherein:

Figure 1 is a diagrammatic view of the burglar alarm system.

Figure 2 is a sectional view taken along 50 the line 2-2 of Figure 1.

Figure 3 is a sectional view taken along the line 3-3 of Figure 1 looking towards the magnet.

Figure 4 is a perspective view of the contact and actuating device mounted upon the 55 door jamb and door respectively.

Figure 5 is a perspective view of the

spring winding disk looking at the inner face thereof.

Figure 6 is a sectional view taken along the line 6-6 of Figure 1. 60

This burglar alarm is provided with a signal or electric bell 10 which is mounted upon a supporting board 11 and may be located at the most desirable point in a residence. The board 11, in addition to the bell, 65 carries contact posts 12, 13, 14 and 15 and the bell is provided with the usual posts 16 and 17. An electro-magnet 18 is carried by supporting brackets 19 and 20 and has one terminal of its coil connected with the post 70 13 and the second terminal of its coil connected with the post 15 from which extends a wire connected with the bell post 17. The terminal post 12 is connected with the terminal post 15 and is in circuit with the battery or other source of current 21 through the medium of the wire 22, the second wire 23 being connected with the terminal post 14. Wires 24 and 25 lead from the terminal posts 13 and 14 and are connected with the 75 contacts 26 and 27 to be hereinafter more fully described, a switch 28 being provided so that the circuit through the magnet may be rendered inoperative when desired.

From the above description it will be 85 readily seen that when the contacts 26 and 27 are in engagement and the switch 28 closed, a circuit will be established through the electro-magnet thus energizing the magnet and causing the armature pin 29 thereof 90 to be drawn inwardly.

The armature pin 29 of this magnet 18 carries a head 30 which limits inward movement of the pin and which is engaged by the spring 31 serving to normally retain the 95 pin in an extended position. The core 32 of this magnet extends beyond the lower end thereof as a tube 32' and journals a sleeve 33 having at one end a disk 34 and at the opposite end a spring housing 35 in 100 which is positioned a spring 36. The armature pin 29 is slidably mounted in a longitudinally extending opening formed in the core 32 and is provided with a finger 37 which extends through a side slot 37' in the 105 tube 32' and is adapted to fit into a notch 38 formed in the lower end portion of the sleeve 33 and holding the sleeve against rotary movement when seated in the notch. When the magnet is energized and the armature pin is drawn inwardly against the 110 tension of the spring 31, the finger will move

out of the notch thus releasing and permitting this sleeve to rotate under urgency of the spring 36. A spring winding disk 39 closes the spring housing and carries pins 40 which engage the free end of the spring 36. The disk will be put in place and after being turned to tighten the spring will be secured by a screw 40'. When the armature pin moves to the inoperative position, 10 the spring will rotate the sleeve and the contact arm 41 carried thereby will engage the contact 42 carried by the bracket 20. This bracket 20 further carries a terminal screw 43 which is connected with the terminal screw 16. A terminal screw 44 is carried by the base board 11 and is connected with the terminal screw 14 by wire 45 and with the disk 39 by the short wire 46. It will thus be seen that when the magnet is 20 energized and the sleeve released and turned by spring 36 to bring the contacts 41 and 42 into engagement a circuit will be established through the bell thus causing the bell to ring until the sleeve is returned to 25 the normal position through the medium of the handle 47. When returned to the normal position, the spring 31 moves the pin 29 to bring the finger thereof into the notch of the sleeve to hold the sleeve in the set position.

The contact arms 26 and 27 are connected with the insulating base 48 which will preferably be formed of fibre. The contact arms will be formed of metal having sufficient 35 resiliency to permit the arm 27 to be swung into engagement with the arm 26, the end portion 26¹ of which extends across the thickened end portion of the arm 27. This thickened end portion of the arm 27 has a 40 beveled end which extends beyond the base 48 and is adapted to pass through the cutout 49 of the plate 50 secured to the door 51. This plate 50 carries a plunger 51 which has a pin 52 slidably mounted in the opening 45 of the lug 53, a spring 54 being provided to normally retain the plunger in an extended position and a strap or bracket 55 being provided to guide the sliding movement of the plunger. The end of this plunger is beveled 50 or under-cut as shown so that when the door is closed the plunger may ride past the contact 27. In order to permit the door to be closed and opened without the alarm being given, the plunger may be retained in a 55 retracted position by any suitable means or the contact 26 or 27 may be swung to an inoperative position.

When in use, the burglar alarm will be installed as shown in the diagram in Figure 60 1. The signal will be placed at a suitable point in a house and the battery wires 22 and 23 connected with the terminal posts 12 and 14. The contact carrying base plate 48 and the plate 50 which carries the plunger will 65 be mounted upon a door jamb and door

respectively, at which it is desired to protect against unauthorized opening, and the contacts 26 and 27 connected with the terminal posts 13 and 14 by the line wires 24 and 25. If an unauthorized person attempts 70 to enter through the door 51, the plunger will engage the contact arm 27 and move the same into engagement with the contact arm 26 thus closing the circuit through the electro-magnet and causing the magnet to be 75 energized. This will draw the armature pin inwardly and move the finger 37 out of the notch in the sleeve thereby releasing the sleeve and permitting the spring 36 to swing the sleeve to bring the contacts 41 and 80 42 into engagement. This closes the circuit through the bell and the bell will ring until the sleeve is returned to the original position. The spring 31 will then move the pin 29 to bring the finger thereof again into the 85 notch of the sleeve thus retaining the sleeve in the desired position. It will thus be seen that there has been provided an alarm in which the movement of a door toward an open position will cause the bell to ring and 90 that this bell will continue to ring until manually shut off. Therefore, there is no danger of the bell being rung for a very short length of time and failing to wake the occupant of the house in which the alarm 95 is installed. It will be further noted that this is a very simple system which can be easily installed and which does not require the services of an experienced electrician in order to be properly installed.

What is claimed is:

1. A switch mechanism of the class described including a fixed member, a rotary member journaled thereon having a contact member, a contact member in circuit 105 with said contact member and engageable thereby, a spring within the rotary member to urge rotation thereof, detent means for the rotary member slidably mounted in a fixed member and having a detent member 110 projecting therethrough to normally restrain movement of the rotary member.

2. A switch mechanism of the character described having a fixed member provided with a tube having a slot therethrough, a 115 rotary member journaled on the tube having a laterally extending wall provided with a contact and having a housing, a contact in circuit with said contact and engageable thereby, a rod slidable in the fixed member 120 having a lug extending through said slot, said housing having a notch to receive said lug, and a spring engaging the rod and fixed member to maintain the rod in the notch, and means in the housing to urge movement 125 of the rotary member.

3. A switch mechanism of the character described having a fixed member provided with a tube having a slot therethrough, a rotary member journaled on the tube having 130

a laterally extending wall provided with a contact and having a housing open at one end, contact in circuit with said contact and engageable thereby, a rod slidable in the 5 fixed member having a lug extending through said slot, said housing having a notch to receive said lug, a spring engaging the rod and fixed member to maintain the lug in the notch, a spring in said housing to urge 10 movement of the rotary member, a closure for the open end of the housing having pins

engaging the last spring, the closure being turnable on the tube to wind the last spring and means to rigidly secure the closure to the tube.

15

In testimony whereof I affix my signature in presence of two witnesses.

GIOVANNI ANTOFILLI.
